SAND PUMP
 Fred W. Cook, Odessa, Tex.
 (P.O. Box 1672, Lubbock, Tex.)
 Filed Sept. 13, 1960, Ser. No. 55,736
 10 Claims. (Cl. 175—308)

This invention relates to well tools and more particularly to those oil well tools commonly known as sand pumps.

This invention is an improvement over the application of Ray A. Yates, Serial No. 705,531, filed December 27, 1957, for Sand Pump; owned by a common assignee, now Patent No. 3,003,562.

An object of this invention is to provide a tool for pumping small loose material from the bottom of a well.

Another object of this invention is to provide such a tool which is easy to repair.

Another object is to provide such a tool which is positive in action and has positive means for loosening the parts should they become stuck.

A further object is to provide a tool which has dual utility; first, in breaking up hard material, and pumping it within its body; and second, loosening and sucking up large amounts of loose material such as sand.

A further object is to provide a novel method for removing items which have been placed in the well such as iron bridging plugs, production packers, cement retainers, etc.

A further object is to provide a novel method of removing stuck tubular material from within a well.

A further object is to provide a tool which may be run with commercially available equipment which does not require expensive additional equipment to operate.

A further object is to wash around stuck material in a well.

Still further objects are to achieve the above with a device that is sturdy, compact, durable, simple, and reliable, yet inexpensive and easy to manufacture.

The specific nature of the invention as well as other objects, uses, and advantages thereof will clearly appear from the following description and from the accompanying drawing, the different views of which are not necessarily to the same scale, in which:

FIG. 1 is a sectional view of a tool according to this invention.

FIG. 2 is an enlarged sectional view of a portion thereof showing details.

FIG. 3 is a perspective view of the shoe that would be used to drill, being the same as shown in FIG. 1.

FIG. 4 is a perspective view of a sand shoe.

FIG. 5 is a partial sectional view of a washover shoe with a stuck object shown in phantom.

As may be seen in the drawing, a tool built according to this invention has tubular housing 10. The housing functions as a cylinder for the pump. The pump includes pistons 12 and valves 14. Each piston also includes a valve seat.

Shoe 16 is attached to the bottom of extension 18 of the housing. The extension 18 is welded to the bottom of tubular member 10. The extension 18 includes short portion 20 which telescopes within the end of member 10. This telescoped portion 20 acts as a stop for plunger 19. The shoe has a threaded pin which fits into a threaded box of extension 18. At the top of the shoe there is a lug 21 which has hinged thereto flapper valve 22.

The flapper valve is designed so that it can open rather fully within the tubular portion of extension 18. However, it is designed so that it cannot open a full 90 degrees but stops at least 5 degrees short of vertical. When fluid ceases to flow into the body of the housing, the valve closes positively and certainly.

2

Two types of bottom shoes are provided. One has a drill bit 24 on the bottom thereof. The drill bit is made of high quality metal such as 4130 alloy steel heat treated to a Brinell hardness of 290. In addition, the tip itself is coated with carbide and sharpened to a knife edge. With the weight of the entire tool it is possible to drill through tough materials with this. Concrete and the like present no problem at all to this tool. However, certain malleable alloys such as some of the alloys of aluminum and certain iron fittings are difficult to drill. However, with this tool, I have found that I am able to drill out iron bridging plugs, iron production packers, metal cement retainers, and other materials. One of the most difficult things, I have found, to break up and remove are rubber packers and other rubber material which have vulcanized in place. I have found with this tool that I have been able to chop them up in sufficiently small pieces to suck them up into the body of the tool and remove them from the well within the tool. The drill bit has large fluid passages 25 whereby the liquid and debris may be sucked within the body of the tool. For purposes of a generic terminology all the various and sundry obstructions found in the well will be called slugs regardless of whether they are rubber, metal, cement, natural, or man-placed.

25 The shoe illustrated in FIG. 4 has an annular bottom 26. This makes the tool more efficient in quickly sucking pulverulent material such as sand, either natural or artificially introduced.

Pump top 28 is threaded into the top of housing 10 by threaded pin at the bottom of the top. The top has a set screw (not shown) to insure that the top does not come disconnected from the rest of the housing. Fishing neck 30 is at the extreme upper portion of the top. The bottom of the pin of the pump top is of lesser diameter 35 than the inside of the tubular housing thus providing the plunger 19 with a stop.

Although there will be a certain clearance between the top 32 of the plunger 19 and the inside of the bore extending through the pump top, additional fluid passages 34 in the form of circular ports through the top of housing 10 are provided.

40 The plunger is in the form of a solid rod which extends from cable socket 36 at the top. The cable socket 36 is of standard form and has a box on the lower end 45 so that it may be attached to a pin at the top of the plunger. The cable socket performs the normal function of being means for attaching a cable 38 to the plunger.

45 The valves 14 have a convex conic top 39 which is the 50 valve proper. Otherwise, they are generally cylindrical in shape and are shrunk fit upon the plunger 19. In addition to this, they are also held by a dowel 40 extending through them and the plunger. The lower portion of 55 each valve has a radial cut-out 42. This cut-out provides a fluid passage upon the down stroke of the plunger as will be explained later. The uppermost valve 44 is actually a stop and not a valve, however, it is the same shape and size as the rest and will be referred to as a valve. It is not shrunk fitted and doweled onto the plunger but 60 is threaded thereto and welded. Top valve 44 is attached more securely because it absorbs all of the shock when the plunger is violently raised and hits the lower end of pump top 28. The plunger picks up the entire housing weight and this must all be absorbed in stop 44.

65 The pistons 12 are made of brass. I have found that this works well when the housing 10 is of steel and the valves 14 are of steel. They work satisfactorily to be brass coated, however, it is more economical to make them of solid brass than to coat the steel. Each valve 14 70 has a top and bottom integral annular rings 46 which are in sliding engagement with the housing 12. Square notch

48 is between the rings. The rings are in fluid sealing relationship with the inside of the housing 10 and have only sufficient clearance for mechanical working. The fluid pumped will be heavily laden with debris such as sand. The inside of the pistons 12 have sufficient clearance so that there is a fluid passage space between the inside bore of the pistons 12 and the plunger. Likewise, the valves are sufficiently small in diameter so that there is a fluid passage space between the outside of the valves and the housing 10. The bottom of each piston 12 has a concave conic depression 50 which is correlative to the convex conic top 39 of the valves. This concave surface is the valve seat proper. I have found it desirable to make annular serrations within the valve seat so that a grain of sand will not prevent the seating of the valve in the valve seat. I.e., if both surfaces were smooth, a grain of sand on 39 would prevent the valve from fully seating and permit a fluid flow therebetween. However, by making the valve seat serrated, a grain of sand has the possibility of fitting into one of the serrations so that the fluid seal is made.

The only wearing surfaces are between the pistons and the housing wall 10, and the valve surfaces on the pistons 12. Therefore, the main parts that need to be replaced through wear is the piston. This may be done by removing the various valves from the plunger and removing the pistons and replacing new ones. Of course, the plunger may be removed from the tool by unscrewing the top 28 from the housing 10 and removing the entire plunger. Normally the bottom valve member will be welded to the plunger. Therefore, should any of the valve members break loose, they will be retained upon the plunger. However, this is a light weld and could be easily removed when the valves are removed for replacement.

Also in operation, should any of the pistons become stuck to the housing because of sand or other foreign materials, they may be dislodged readily and positively by jerking up on the cable or dropping the weight of the plunger on them. In this regard, the length of the plunger is varied so that sufficient weight is accumulated. This is particularly important in smaller models because the tool has been manufactured successfully with as small as 1 and $\frac{1}{8}$ inch outside diameter.

In operation, the tool is lowered into the well so that the housing rests upon the bottom. If it is necessary to drill out some slugs in the well, the tool may be used as a drill by reciprocating the cable 38. After the material has been drilled up the plunger is lowered within the housing. The flapper valve 22 will be closed and the pistons will rise against the bottoms of valves 14. There will be a fluid flow around the outside of the valves 14, the inside of the pistons 12, and through the annular cutouts 42. The plunger volume will displace some fluid and it will flow out ports 34. When the plunger reaches the bottom it is raised by tension on the cable 38. The valves contact the valve seats 50 raising the pistons. This closes the fluid passages. Actually for fluid to leak from above top valve 44 it would have to follow the tortuous path around three pistons or through three valves.

I have found the tool to be quite useful for fishing for tubular material, the top of which is plugged. It is plugged with a slug as discussed above or plugged by sand or shale. According to the novel method, the tool would be used to drill out the plugged tubular material within the well. The tool would clean out a considerable extent of the bore of the plugged tubular material. After this was done, the stuck material could be removed by the conventional practice of lowering a charge of explosive material within the tubular material and setting off the charge and removing the piece thus freed. Often the detonation will cause sufficient cave-in so that the next section sought to be removed will also be plugged. Therefore, the tool according to my invention can again be used to remove the debris plugging the tubular material so that another explosive charge may be lowered within it.

It will further be understood that in operation that the sand and debris will not only accumulate in the lower portion of the extension 18 but will come up within a considerable portion of the housing 19. In this regard, 5 ordinarily the tool will be built with the housing approximately 21 feet long whereas the plunger itself will have a length of less than about 4 feet. Considerable debris may be in the bottom portion of the housing 10 and still have room for a plunger stroke. I have found it quite successful to use three pistons and three valves and the stop 44.

FIG. 5 illustrates another shoe of the annular type. More exactly, the long shoe 16 illustrated in this FIG. 5 is similar to a washover shoe. The problem is sometime encountered when a fish is covered by the debris. Here the term "fish" is used to mean any object to be removed from within the well. Techniques have been developed for removing these objects providing that a grapple may be attached to the fishing neck F. However, these fishing necks may be completely covered by debris such as sand.

In use, the long shoe 16 is placed upon the end of the tool extension 18 the same as the other shoes. It is lowered into the well, there are small hard teeth on the bottom so that it may drill into the crust of sand. With the pump operating as before, the debris is removed by pumping debris laden fluid from around the fishing neck of the fish. The bottom of the pump is a container for debris. Then this tool is removed and a grapple is lowered into the well to remove the object by conventional methods.

It will be noted that the long shoe illustrated in FIG. 5 has rather thin walls so it can go quite close to the surrounding casing or the well side walls, and still fit over as large a fish as possible. Also it will be noted that it is rather elongated, i.e., that it is over twice as long as it is in diameter. Otherwise stated, the diameter of the tube is less than $\frac{1}{2}$ the length.

I have found that with this tool with the shoe of FIG. 3 that I can break up and pump pieces that heretofore have required a milling shoe to be lowered upon the end of a rotary drill stem. I consider this novel that I can remove slugs, metal, or rubber, with this cable tool which slugs heretofore required rotary milling tool. Indeed, one of the things that I have been able to remove with this is the aluminum alloy known as "Kirksite."

It will be apparent that the embodiments shown are only exemplary and that various modifications can be made in construction, materials, and arrangement within the scope of the invention as defined in the appended claims.

I claim as my invention:

1. A well tool comprising: a tubular housing, a shoe on the bottom of the housing, a check valve on top of the shoe, a solid plunger in the housing, a rope socket on top of the plunger, a stop on the housing above the check valve, a second stop at the top of the housing, the stops being means for limiting the travel of the plunger, a plurality of valves with convex conic tops attached to the plunger, the valves having radial cut-outs at their lower edge, an annular fluid passage area between the periphery of the valve to the inside of the housing, an annular piston surrounding the plunger above each valve, an annular fluid passage area between the piston and the plunger, the bottom of each piston having a concave conic valve seat correlative with the conic top of the valve, the valve seat having annular serrations therein, and the outside periphery of the valve seat in sliding fluid sealing contacts with the inside of the housing, the outside periphery having a square circumferential groove therein.

2. The invention as defined in claim 1 wherein the valves are made of steel and the pistons from brass.

3. The invention as defined in claim 1 wherein the shoe has a chisel drilling bit of hardened steel sharpened to a knife edge on the bottom thereof.

4. The invention as defined in claim 1 wherein the shoe has an annular lower edge for sucking up pulverent material.

5. A well tool comprising: a tubular housing, a check valve at the bottom of the housing permitting fluid to enter but prohibiting its leaving, a solid plunger in the housing, means on top of the plunger for attaching a cable thereto, means at the top of the housing and the bottom of the housing for limiting the travel of the plunger, a plurality of valves with convex conic tops attached to the plunger, the valves having radial cutouts at their lower edge, an annular fluid passage area between the periphery of the valves and the inside of the housing, an annular piston surrounding the plunger above each valve, an annular passage area between the 15 pistons and the plunger, the bottom of each piston having a concave conic valve seat correlative to the conic top of the valve, and the outside periphery of the valve seat in sliding fluid sealing contact with the inside of the housing.

6. The invention as defined in claim 5 with the addition 20 of annular serrations on the surface of the valve seat.

7. The invention as defined in claim 5 wherein the valves are made of steel and the pistons from brass.

8. The invention as defined in claim 5 with the addition 25 of a chisel drill bit of hardened steel sharpened to a

knife edge, the bit attached to the bottom of the housing.

9. The invention as defined in claim 5 with the addition of an elongated tube attached to the bottom of the housing the tube being adapted to surround an object stuck in an oil well to clean debris from around the objects.

10. The invention as defined in claim 9 wherein the diameter of the tube is less than half the length of the tube.
